UNITED STATES PATENT OFFICE

DAVID B. DAVIES, OF SHELTON, WASHINGTON

CIRCULATING SYSTEM FOR PULP DIGESTERS

Application filed August 18, 1928. Serial No. 300,433.

This invention relates to a circulating system for pulp digesters and more particularly to an apparatus and method for obtaining rapid circulation of digester liquor during the process of cooking chips for the preparation of sulphite pulp.

In the so-called Ritter-Kellner or quick cooking process, after the digester is filled with chips and acid, direct steaming of the contents of the digester is started in the usual way. In the case of large digesters, especially, and to some extent in the case of smaller digesters. It is extremely difficult to effect a uniform rise of temperature throughout the contents of the digester during the heating up period. Furthermore, actual cooking of the chips does not effectually begin until all parts of the digester contents reach 110 to 120° C. and any time wasted in bringing this temperature about is a loss to the entire cook, since the last portions to reach cooking temperature govern the finishing of the cook. Moreover, uneven temperature in different parts of the digester result in pulp lacking in uniform qualities and in lower yields.

In some instances, pumps and other mechanical devices have been employed to effect circulation of the digester liquor, but such devices are costly to maintain and get out of order frequently.

It is therefore an object of this invention to provide an apparatus for circulating digester liquor having no moving parts and capable of effecting a rapid circulation within the digester to insure rapid heating and uniform temperatures throughout.

Other and further important objects of this invention will be apparent from the disclosures in the specification and the accompanying drawing.

This invention (in a preferred form) is illustrated in the drawing and hereinafter more fully described.

On the drawing:

The drawing is an elevational view of a pulp digester showing a circulating system installed thereon, with parts broken away and in section.

The reference numeral 1 indicates a vertical stationary digester of standard type

such as is used in cooking by the sulphite process with direct steam. The auxiliary tank 2, according to the principles of this invention, is connected to the upper portion of the digester 1 by means of a pipe line 3 entering said auxiliary tank as at 4. A perforated strainer 14 serves to protect the opening of the pipe 3 into the digester 1 to prevent chips from getting into said pipe line 3.

A second pipe line 5 connects the lower portions of the digester 1 and auxiliary tank 2. A valve 6 is positioned in the pipe line 3 conveniently close to the digester, and a check valve 26 near the tank 2. Said pipe line 5 is likewise provided with a valve 7 and a check valve 15, the latter being inserted in the line 5 between the valve 7 and the tank 2 to prevent a reverse flow of liquor from the digester 1 into the tank 2. The auxiliary tank 2, which may be of any desired shape or size, is preferably positioned on a level with the lower portion of the digester. Said tank 2 is built to withstand the usual steam pressures in a sulphite mill and is lined with acid resistant brick 8, or the like. A steam line 9 enters the top of the auxiliary tank 2 as at 10 and is provided with a valve 11 for controlling the steam flow. A check valve 16 is inserted in the steam line 9 between the valve 11 and the opening 10 in the tank 2 to prevent an accidental flow of liquor into the line 9 should the steam pressure therein at any time fall below the digester pressure while the valve 11 is open.

The exhaust line 12, also connected near the top of the tank 2 is provided with a relief or poppet valve 13 for exhausting the gas pressure within said tank.

During the steaming of the digester to bring the contents up to cooking temperatures, circulation of the digester liquor within the digester is effected by the operation of my circulating system as follows: Keeping the other valves closed, the valve 6 is opened to permit liquor from the digester to enter the tank 2 through the pipe line 3 and check valve 26 until the pressures in the digester and tank are equalized. As soon as the tank 2 is filled with digester liquor, valve 6 is closed and valves 7 and 11 are opened.

Steam under higher pressure than that within the digester 1 is thus introduced through the steam line 9 into the top of the auxiliary tank 2 and by virtue of its greater pressure will force the liquor contained therein out through the pipe 5 into the bottom of the digester 1.

As soon as the entire body of the digester liquor is discharged from the tank 2, valves 7 and 11 are closed and the poppet valve 13 opened to bring the interior of the tank 2 again to atmospheric pressure. The cycle is then repeated as before.

The check valve 26 automatically prevents steam or liquor from passing out of the tank 2 through the pipe line 3 and the check valve similarly prevents a reverse flow through the pipe 5. Accordingly it is possible to keep both valves 6 and 7 open during the entire circulating operation and rely entirely upon the check valves 15 and 26 automatically opening and closing in accordance with the fluctuation of pressure within the tank 2.

It will be understood that the opening and closing of the valves 11 and 13 may be automatically controlled, as by an automatic timing device, or may be partially or wholly controlled by a float device within the tank 2. Furthermore it will be understood that in place of the steam used to discharge the digester liquor from the auxiliary tank 2, hot gas relieved from another digester at higher pressure than the digester being steamed may be employed. The tank 2 may, if desired, take the form of an enlarged pipe.

Obviously more than one auxiliary tank, arranged as described, may be employed with a single digester. Also, the pipe lines 3 and 5 may be connected to different levels of the digester 1 than shown, provided the connections with the digester are at vertically spaced points. Preferably, however, the connections are as shown, so that the circulation will cause uniform temperature throughout the digester independently of the irregular absorption of heat during the steaming process.

The use of my circulating system is thus seen to provide a rapid and uniform circulation of the digester liquor throughout the digester during the cooking process. The system gives unlimited circulation of the cooking acid and thus brings the whole mass in the digester rapidly to an equal temperature, resulting in a much more uniform grade of pulp and in higher yields.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. A liquor circulating system for pulp di-

gesters, comprising in combination with a digester, an auxiliary container, valve controlled connections from said container to said digester, exhaust means on said container and a fluid pressure connection to said container for forcing liquor from said container into said digester.

2. A liquor circulating system for pulp digesters, comprising in combination with a digester, an auxiliary tank positioned below the liquor level in said digester, valve controlled connections from said tank to said digester at points near the top and bottom of said digester respectively, an exhaust valve on said tank and a steam line connection opening into the top of said tank for forcing liquor from said tank into said digester.

3. The method of circulating liquor in pulp digesters, which comprises allowing a portion of the liquor from near the top of a digester to flow into an auxiliary chamber introducing steam under greater pressure than exists in said digester into said chamber to force said portion into the lower part of said digester, and exhausting the steam from said chamber.

4. The method of circulating liquor in pulp digesters, which comprises intermittently allowing a portion of the liquor from near the top of a digester during the steaming of the digester to flow by reason of the pressure within the digester into an auxiliary chamber, introducing steam under greater pressure than exists in said digester into said chamber to force said portion into the lower part of said digester, and exhausting the steam from said chamber.

5. The method of circulating liquor in pulp digesters, which comprises allowing a portion of the liquor from one part of the digester during the heating up of the contents of the digester to flow into an auxiliary chamber subjecting said portion of liquor in said auxiliary chamber to higher direct steam pressure than exists in said digester to force said liquor portion into another part of said digester and thereby obtain uniform heating up of the contents of said digester, and exhausting the steam from said chamber.

6. The method of circulating liquor in pulp digesters, which comprises allowing a portion of the liquor from one part of the digester during the heating up of the contents of the digester to flow into an auxiliary chamber and subjecting said portion of liquor in said auxiliary chamber to higher direct steam pressure than exists in said digester to force said liquor portion into another part of said digester and thereby obtain uniform heating up of the contents of said digester, bringing the pressure in said auxiliary chamber back to atmospheric and repeating the cycle.

7. The method of circulating liquor in pulp digesters, which comprises intermittently allowing a portion of the liquor near the top of

the digester to flow into an auxiliary chamber, introducing steam at greater than atmospheric pressure into said auxiliary chamber to force said portion into the lower part 5 of the digester, and bringing the pressure of the auxiliary chamber back to atmospheric pressure.
